UNITED STATES PATENT OFFICE.

RICHARD GILLMAN, OF LOWELL, MASSACHUSETTS; SAMUEL H. SEWARD,
ADMINISTRATOR OF THE ESTATE OF RICHARD GILLMAN, DECEASED.

BOLSTER FOR SPINNING-SPINDLES.

SPECIFICATION forming part of Letters Patent No. 223,724, dated January 20, 1880.

Application filed July 30, 1879.

To all whom it may concern:

Be it known that I, RICHARD GILLMAN, of Lowell, in the county of Middlesex and State of Massachusetts, have invented certain new and useful Improvements in Bolsters for Spinning-Spindles; and I do hereby declare that the following is a full, clear, and exact description of the invention, which will enable others skilled in the art to which it appertains to make and use the same, reference being had to the accompanying drawings, which form a part of this specification.

Figure 1 is a side view. Fig. 2 is a vertical central sectional view, and Fig. 3 is a horizontal section on the line $\alpha\alpha$ of Fig. 1.

Corresponding parts in the several figures are denoted by like letters of reference.

This invention relates to bolsters of self-oiling spindles, more especially for spinning frames, jacks, and mules; and it consists in certain improvements in the construction of the same, which will be hereinafter fully described, and particularly pointed out in the claim.

In the drawings hereto annexed, A represents the spindle, which may be of any suitable construction, and is journaled in the step B and bolster C, to both of which my invention is applicable, although I shall describe it in connection with the bolster only. The latter, like the step B, is secured in its rail by a setscrew, E, or other suitable means.

The lower end of the bolster is provided with a permanent shank, F, at a short distance above the upper termination of which it is swelled, so as to form a chamber, H, having at its upper end an opening of sufficient size to receive a loose bushing, G, extending downward to the top of shank F, and forming with the latter the bearing for the spindle.

At its upper end the bushing G is provided with a flange, I, covering the top of the cylindrical chamber H. The latter, which forms the oil-chamber, is fed through an opening, J, in its top, access to which is had through a notch, K, in flange I, which may be turned so as to bring the notch K over the opening J. A pin, L, fitted in the top of the oil-chamber, beside the opening J, confines the motion of the movable bushing, as shown.

In operation, the oil escapes from the chamber H to the spindle-bearing between the shank F and bushing G, the rotary motion of the spindle having a tendency to draw the oil from the chamber in sufficient quantity to lubricate the bearing. When the spindle is at rest the escape of oil is prevented by the flange I of bushing G, which forms a cover sufficiently tight for this purpose.

If desirable or necessary, one or more small notches may be cut in the lower end of the movable bushing, thereby permitting the oil to escape more freely.

Having thus described my invention, I claim and desire to secure by Letters Patent of the United States—

The combination, with the bolster C, having the shank F and the oil-chamber H, the top of which is provided with opening J and pin L, of the loose bushing G, having notch K, arranged and operating substantially as herein described, and for the purpose shown and specified.

In testimony that I claim the foregoing as my own I have hereto affixed my signature in presence of two witnesses.

RICHARD GILLMAN.
